(57) **CLAIM**

The ornamental design for an inhaler, as shown and described.

DESCRIPTION

1. Inhaler

The design is the visual features of the inhaler, shown in solid lines in the drawings; **1.1** is a front perspective view of the inhaler; **1.2** is a front view thereof, and back view being identical; **1.3** is a first side view thereof, and the other side view being identical; **1.4** is top view of the thereof; and **1.5** is a bottom view of the thereof.

The broken lines show portions of the inhaler that form no part of the claimed design.

1 Claim, 5 Drawing Sheets
